Attorney.

UNITED STATES PATENT OFFICE.

CHARLES DAY, OF STOCKPORT, ENGLAND.

FUEL VALVE FOR INTERNAL-COMBUSTION ENGINES.

Application filed March 10, 1923. Serial No. 624,291.

To all whom it may concern:

Be it known that I, CHARLES DAY, a British subject, residing at Highfield, Mile End, Stockport, in the county of Chester, England, have invented a certain new and useful Improvement in Fuel Valves for Internal-Combustion Engines, of which the following is a specification.

In connection with the valves controlling the admission of fuel oil to the cylinders of oil engines, and particularly of engines of the Diesel type where compressed air is used to inject the fuel, it has hitherto been customary to use a gland with fibrous or metallic packing to prevent leakage of compressed air past the valve spindle.

Such a gland if improperly packed, may cause sticking of the valve, hence various devices have previously been used to overcome this difficulty.

Also it has hitherto been customary for each such valve spindle to be formed in one piece extending from the working valve face to right up to the outer guide and to the operating lever, thus necessitating extreme accuracy in the alignment of the various surfaces guiding the spindle.

This invention has for its objects—(1) the dispensing with the need for packing and the doing so in a simple and inexpensive manner, which can be readily applied to many existing engines with little alteration,—(2) the removal of the necessity for extreme accuracy of alignment of the whole length of the surfaces guiding the spindle.

I attain these objects by the means illustrated in the accompanying drawing, in which—

Figure 1 is a detached view in vertical section of a fuel valve for internal combustion engines.

Figure 2 is a detached view in vertical section of a portion of a fuel valve and illustrates a modification.

Figure 3 is a detached view in vertical section of a fuel valve and illustrates another construction.

Referring to Figure 1 of the drawings in the construction illustrated therein, the fuel valve is divided into two parts A^1 and A^2 connected by means of a sleeve coupling B and cotters C, the cotters and the slots in which the cotters are inserted being so arranged as to allow a little play both in the direction of the axis of the fuel valve, and in regard to the alignment of the two por-

tions, whilst giving a definite means of lifting the lower portion A^1 by the upper portion A^2 .

Instead of a sleeve and cotters, other forms of connection may be used, as for instance that shown by Figure 2, where collars are formed on the portions A^1 and A^2 , and a surrounding sleeve B with collars formed inside is fitted in such a way as to allow of the play previously referred to, whilst giving a definite means of lifting the lower portion A^1 by the upper portion A^2 . To facilitate the attachment of the sleeve B this may be made in halves, the halves being held in place by an outer casing C'.

On the upper portion of the spindle A^2 a valve face E is formed in such a position that this valve face rests on a seat formed in the surrounding casing F or attached thereto, whenever the valve is not being lifted by its operating lever. A spring D may if desired be placed between the portions A^1 and A^2 .

Whether the arrangement illustrated in Figure 1 or that illustrated in Figure 2 or an alternative mode of connection be adopted, longitudinal and lateral flexibility is to be provided, so that when the upper valve face E, i. e. the valve face on portion A^2 rests on its seat, the valve face G, at the bottom of the lower portion A^1 will also rest on its seat without any restraint from the coupling, and so that proper movement of the valve will not be interfered with by slight errors of alignment between the two portions A^1 and A^2 .

When the upper portion A^2 is lifted by the operating lever (not shown), the first movement of this will be to take up the clearance at the cotters C shown in Figure 1, or at the collars shown in Figure 2. When this clearance has been taken up, the lower portion A^1 will be lifted. The outside spring which presses on the upper portion A^2 will when the lever is not lifting the valve, press the valve face E against the seat formed on the casing, and thus prevent leakage of air past the spindle A^2 .

In cases where to open the fuel valve it is necessary to move the spindle in the opposite direction, the valve face E on the portion A^2 will be on the underside of the guide formed by the casing as shown in Figure 3 and the portion A^2 instead of pulling the portion A^1 will now push it to open the fuel valve. The valve face E on the portion A^2 when pressed

against the seat formed in the casing or attached thereto, will prevent leakage past the spindle A². As in this case the compressed air in the fuel chamber tends to force the 5 lower portion A¹ of the fuel valve outwards, a spring H has to be provided to close this part against such pressure.

In Figure 3, A¹ and A² are the two portions of the valve spindle. When the upper 10 portion A² is pressed downwards by its operating lever, (not shown) it presses on the adjustable cap attached to the lower portion A¹ and opens the fuel valve face G to admit of fuel oil being blown into the cylinder. When 15 the portion A² is released by the operating lever the portion A¹ is lifted by the spring H, thus closing the valve G and the air pressure forces the valve E against its face and prevents leakage past the spindle A². 20 Whether the arrangement adopted is that shown in Fig. 1, Fig. 2 or Fig. 3, leakage past the spindle can only take place during the period that the valve E is off its seat, which period is very small compared with its closed 25 period.

What I claim is—

1. In an internal combustion engine using compressed air for the injection of fuel, a two part fuel valve the parts whereof are 30 separate but in line with each other; a valve on the outer part of the fuel valve; a fuel valve casing; and a valve seat on the said casing adapted to cooperate with the valve on the said outer part and prevent air leakage 35 from the casing during practically the whole of the period the fuel valve rests on its seat.

2. In an internal combustion engine using compressed air for the injection of fuel, a 40 two part fuel valve the parts whereof are separate but in line with each other; a fuel

valve casing; means on the fuel valve and the casing for preventing leakage of air from the casing at predetermined periods; and a yielding coupling connecting the two parts 45 of the fuel valve together.

3. In an internal combustion engine using compressed air for the injection of fuel, a two part fuel valve the parts whereof are 50 separate; a fuel valve casing; means on the fuel valve and the casing for preventing leakage of air from the casing; and a longitudinally and laterally flexible coupling means connecting the two parts of the fuel valve together.

4. In an internal combustion engine using compressed air for the injection of fuel, a fuel valve casing; a fuel valve seat at the inner end of the casing; a valve seat at the outer end of the casing, a sliding member in 55 the casing provided with a fuel valve face to cooperate with the fuel valve seat; a sliding member in the casing provided with a valve face to cooperate with the valve seat at the outer end of the casing; resiliently yielding 60 means arranged between the said sliding members to transmit sliding movement from the one sliding member to the other in a resilient manner; movement transmitting means provided on one of the sliding members and 65 transmitting movement to the other sliding member with a predetermined amount of lost movement.

In testimony whereof, I have signed my name to this specification at Stockport, in the 70 county of Chester, England, this 20th day of February, 1923.

CHARLES DAY.
